UNITED STATES PATENT OFFICE.

HORACE P. BROWN, OF EMERYVILLE, CALIFORNIA.

BINDING BOOKS.

1,001,245.

Specification of Letters Patent. Patented Aug. 22, 1911.

Application filed April 26, 1910, Serial No. 557,697. Renewed February 3, 1911. Serial No. 606,443.

To all whom it may concern:

Be it known that I, HORACE P. BROWN, a citizen of the United States, residing at Emeryville, in the county of Alameda and 5 State of California, have invented new and useful Improvements in Binding Books, of which the following is a specification.

My invention relates to book-binding.

The object of the invention is to provide 10 a practical and satisfactory method of economically binding pamphlets and books, such as telephone books, magazines, and the like.

A common method is to staple or stitch 15 the leaves together; and then bind or cover the book by gluing a piece of heavy paper to the back. Where a book is used considerably, or subjected to any rough usage, the cover comes off, or loosens, or becomes torn 20 at the corners along the back edge, and soon presents a frayed and ragged appearance, and sooner or later the cover is torn off.

By my method I provide a simple, practical substitute for gluing and stitch the 25 cover on at the same time the pad is stitched, thus saving one operation and one handling of the book as over the old method where it was first necessary to stitch the pad and then glue on the cover. Sometimes in addition 30 to this the glued cover was stitched too, but even then the cover was not secured on as well as by my method.

The invention consists of the parts and the construction and combination of parts 35 as hereinafter more fully described and claimed, having reference to the accompanying drawings, in which—

Figure 1 is a perspective view partly broken away. Fig. 2 is a section of a receipt 40 book.

A represents a pad or pile of leaves constituting the book to be bound.

2 is the cover, which may be of any suitable material with a flexible back portion 45 capable of being infolded one or more times with the ends of the leaves, as shown at 3.

4 represents the staples or stitching passed through the cover 2 and pad A; the pad and

the cover being bound at the same time and by the single securing means 4.

The chief feature of the invention is the forming of the infolded portions 3 of the cover, and their insertion into the back of the book. If the book is a thin one a single infold would suffice; if the book is thicker 55 there would usually be two of these infolds, near the top and bottom of the pad, but with a sufficient amount of the ends of the leaves, represented at 5, embraced between an infold 3 and a top or bottom cover so as to 60 prevent the cover from being broken, at 6, when bent over the stub and stitched. This method of infolded cover is particularly useful in making up scrap books or stub receipt books, or wherever it is desired to insert fillers between the leaves. Thus, as shown in Fig. 2, the cover is provided with an infold 3, between the leaves A, the double thickness of the infolded part of the cover providing the necessary space to accommodate 70 the cards or papers which are inserted in between the leaves and permitting the book from bulging when filled.

Having thus described my invention, what I claim and desire to secure by Letters-Pat- 75 ent, is:

1. The combination with the leaves, of a cover having a flexible back portion, said back portion infolded with the ends of the leaves, and securing means passed through 80 the leaves and said infolded portion.

2. The combination with the leaves, of a cover therefor, said cover having a back portion, said back portion having a folded part inserted from the back in between the leaves, 85 and securing means passing through the cover, ends of the leaves, and said infolded part of said back-portion.

In testimony whereof I have hereunto set my hand in the presence of two subscr- 90 ing witnesses.

HORACE P. BROWN.
